J. T. WEBSTER.

CARPET.

No. 17,453.

Patented July 12, 1887.

UNITED STATES PATENT OFFICE.

JOHN T. WEBSTER, OF FLUSHING, NEW YORK, ASSIGNOR TO THE READ CARPET COMPANY, OF BRIDGEPORT, CONNECTICUT.

DESIGN FOR A CARPET.

SPECIFICATION forming part of Design No. 17,453, dated July 12, 1887.

Application filed June 13, 1887. Serial No. 241,229. Term of patent 33 years.

To all whom it may concern:

Be it known that I, JOHN T. WEBSTER, a citizen of the United States, residing at Flushing, in the county of Queens and State of New York, have invented and produced a new and original Design for Carpets; and I do declare the following to be a full, clear, and exact description of the same, reference being had to the accompanying photographic illustration, forming a part thereof.

My novel design consists in a certain ornamental pattern to be printed upon or wrought into ingrain, Brussels, and the various other grades of carpets, in any suitable or preferred colors, the said design being fully illustrated in the accompanying photographic print.

I claim—

The design for carpets, consisting of the ornamental pattern illustrated in the accompanying photographic print.

In testimony whereof I affix my signature in presence of two witnesses,

JOHN T. WEBSTER.

Witnesses:

GEORGE L. KNAM,
GEORGE F. KNAM.
